US00D601989S

(12) **United States Design Patent**
Park et al.

(10) **Patent No.:** **US D601,989 S**
(45) Date of Patent: **** Oct. 13, 2009**

(54) **MOBILE PHONE**

(75) Inventors: **Soon Hyun Park**, Seoul (KR); **Hyun Seung Seo**, Seoul (KR); **Hong Sik Kim**, Gyeonggi-do (KR)

(73) Assignee: **LG Electronics Inc.**, Seoul (KR)

(**) Term: **14 Years**

(21) Appl. No.: **29/325,962**

(22) Filed: **Oct. 9, 2008**

(30) **Foreign Application Priority Data**

Apr. 10, 2008 (KR) 30-2008-0015327

(51) **LOC (9) Cl.** **14-03**

(52) **U.S. Cl.** ..... **D14/138 AD**

(58) **Field of Classification Search** ..... D14/138 R, D14/138 AD, 138 AC, 138 C, 138 G, 191, D14/203.1–203.8, 496, 138 AA, 138 AB, D14/247–248, 137, 147, 218, 341–347; D10/65, D10/78, 104; D13/168; D18/7; 455/566, 455/575.1, 575.3
